JULIUS NASSAUER, OF NEW YORK, N. Y., ASSIGNOR TO OHIO COMB & NOVELTY COMPANY, OF DOYLESTOWN, OHIO, A CORPORATION OF OHIO.

COMB-CLEANER.

1,089,070.

Specification of Letters Patent.

Patented Mar. 3, 1914.

Application filed January 6, 1913. Serial No. 740,561.

To all whom it may concern:

Be it known that I, JULIUS NASSAUER, a citizen of the United States, residing at New York, in the county of New York and 5 State of New York, have invented a new and useful Comb-Cleaner, of which the following is a specification.

This invention has reference to improvements in comb cleaners, and is designed to 10 provide a simple and efficient instrument for removing accumulations of dirt from between the teeth of combs, particularly the type of combs known as hair combs. Such combs are usually provided with two sets 15 of teeth customarily termed coarse and fine teeth. Sometimes the coarse and fine teeth are on the same side of the comb, and, again, combs are made with coarse teeth on one side and fine teeth on the other, or the 20 comb is made with one type of teeth throughout. The dirt accumulates between the teeth at the bases of the teeth and also on the adjacent sides of the teeth, and if the 25 comb is not cleaned for some time the accumulations often become quite hard, especially at the base of the teeth.

The present invention provides a plate-like structure with an edge, and in some forms opposite edges, roughened or toothed 30 so as to readily remove hardened accumulations of dirt between the bases of the teeth of the comb, and in order to prevent injury to the comb, the roughening is usually produced by a succession of spaced notches 35 formed in the edge of the plate, so that there are no pointed projections liable to injure the structure of the comb. For very fine toothed combs the flat plate with edge notches is sufficient, but for the coarser 40 toothed combs such plate will not remove accumulations on the adjacent or facing portions of the teeth of the comb. To provide for this last condition the plate is corrugated adjacent the toothed or roughened edge, thereby increasing the effective 45 thickness of the plate at such points, so that when drawn between two adjacent teeth of the comb, the sides of the plate will engage alternately with the facing portions of the 50 two teeth. These corrugations extend from the edge of the plate into the body of the plate a suitable distance and the remainder of the plate may be plain. Moreover, the 55 corrugations are not perpendicular to the edge of the plate from which they extend,

but are arranged at a slight angle thereto, so that there is a shearing effect of the corrugations upon the dirt adherent to the sides of the teeth. Moreover, the notches forming the roughened or toothed edge of 60 the plate are so related to the corrugations that a notch is made to coincide with the crown of a corrugation and the next notch coincides with the valley of the corrugation with reference to one face of the plate or 65 the crown of the corrugation with reference to the other side of the plate, this giving a suitable set to the teeth where the plate is corrugated. The plate may be provided with a handle portion along one edge or at one end, 70 or the handle portion may be omitted and the plate may have corrugations and a plain portion both on the same edge or the corrugations may be along one edge and the plain portion on the opposite edge, both the corrugated and the plain portion being 75 toothed.

The invention will be best understood from a consideration of the following detailed description taken in connection with 80 the accompanying drawings forming part of this specification, with the further understanding that while the drawings show a practical form of the invention, the latter is not confined to any strict conformity 85 with the showing of the drawings but may be changed and modified so long as such changes and modifications mark no material departure from the salient features of the invention as defined by the claims. 90

In the drawings:—Figure 1 is an elevation of a structure embodying the present invention. Fig. 2 is an elevation of the structure embodying the present invention but differing in some respects from the 95 showing of Fig. 1. Fig. 3 is an enlarged fragmentary view of a portion of the corrugated part of the structure. Fig. 4 is a section on the line 4—4 of Fig. 3.

Referring to the drawings there is shown 100 a plate or lamina-form structure 1 in Fig. 1 and a plate or lamina-form structure 1^a in Fig. 2. In both instances the plate is made of sheet material and is in the main flat or plane. In the structure shown in Fig. 1 one edge of the plate has formed therein a series of notches 2 defining teeth between them, which teeth have blunt points 3. The notches 2 are relatively quite shallow and the blunt pointed teeth are quite small. In 110

the structure shown in Fig. 1 the edge opposite that provided with the notches 2 is formed into a handle portion 4 which may be done by simply bending the flat plate into 5 a cylindrical bead of a suitable diameter to be readily held in the hand of the user. In the structure shown in Fig. 1 the plate 1 is provided with a series of parallel corrugations 5 extending from the notches 2 toward 10 the handle 4 at a slight angle or inclination to the edge having the notches 2. Each corrugation is separated from the next one by a valley representing a corrugation on the opposite side of the plate and the first-named 15 corrugation represents a valley on said opposite side of the plate. The corrugations are so related to the notches 2 that the ridges are coincident with every other tooth and the valleys are coincident with the intermediate 20 teeth when viewed from either side of the device. In Fig. 1 a portion only of the length of the plate is corrugated and the remainder is plain, but the notches extend the full length of the partially corrugated and 25 partially plain edge. In Fig. 2 one edge is corrugated throughout and the opposite edge is plain, while both edges have the notches produced therein. In Fig. 1 the device is adapted at the corrugated end to cleanse 30 coarse toothed combs, while at the other end it is adapted to fine toothed combs. In Fig. 2 one edge is designed for coarse toothed combs and the opposite edge for fine toothed combs. In Fig. 2 the plate 1^a has a perforation 6 near one end intermediate of the 35 notched edges and this perforation may be employed for attaching a handle to the corresponding end of the plate, or it may be employed simply for hanging the device 40 upon a suitable support.

The association of the corrugations and notches causes the teeth between the notches to be in staggered relation or have a set somewhat similar to suitably set saw teeth, 45 wherefore they will the more readily dislodge any hardened dirt which may be found between the teeth of combs at the base of the teeth. The corrugations cannot well be used for fine toothed combs since it would 50 necessitate the employment of a very thin plate for the body of the device, while these combs may be readily cleansed with the plate thick enough to resist bending under normal conditions of use.

55 In the structure shown in Fig. 1 the bending of the plate is further resisted by the handle portion 4 which operates as a stiffening means for what may be termed the

back edge of the device. Of course, the handle portion 4 need not be in one piece with the plate for any ornamental backing may be used where the question of expense is not material.

The invention is susceptible of manufacture as a one piece structure readily stamped out of sheet metal and hence can be made at but a slight advance of the cost of the sheet material of which sheet aluminum is found to be very serviceable, but any other metal or non-metallic material of requisite stiffness may be employed. The blunt teeth formed by the spaced notches 2 are not only effective for the purpose, but present large wearing surfaces which greatly prolong the useful life of the device without injury to the combs which are customarily made of non-metallic materials or soft metals and which would be liable to injury were any sharp portions brought into forcible contact therewith.

80 What is claimed is:—

1. A comb cleaner comprising a plate-like structure with an active edge notched to form a series of teeth, and the body portion provided with corrugations extending to and including the toothed edge, each corrugation being of a width to include a plurality of teeth and the latter being set or staggered with relation one to the other.

2. A comb cleaner comprising a plate-like structure with marginal notches forming teeth of uniform size throughout, with a fractional portion of the toothed margin provided with corrugations extending back into the body of the structure and each corrugation being of a width to include a plurality of teeth set or staggered with relation one to the other by said corrugations.

3. A comb cleaner comprising a plate-like structure with an active edge notched to form a series of teeth, and the body portion provided with corrugations extending to and including the toothed edge and inclined with respect thereto, each corrugation being of a width to include a plurality of teeth and the latter being set or staggered with relation one to the other by said corrugations.

95 In testimony that I claim the foregoing as my own, I have hereto affixed my signature in the presence of two witnesses.

100 JULIUS NASSAUER.
